US0D1034589S

(12) **United States Design Patent** (10) **Patent No.:** **US D1,034,589 S**
(45) **Date of Patent:** **** Jul. 9, 2024**

(54) **HARD DISK DRIVE ADAPTER**

(71) Applicant: **Shenzhen Huidegui Science & Technology Development Co., Ltd.**, Shenzhen (CN)

(72) Inventor: **Liang Yang**, Shenzhen (CN)

(73) Assignee: **Shenzhen Huidegui Science & Technology Development Co., Ltd.**

(**) Term: **15 Years**

(21) Appl. No.: **29/854,462**

(22) Filed: **Sep. 26, 2022**

(51) LOC (14) Cl. **14-02**

(52) U.S. Cl.

USPC **D14/348**

CLAIM

The ornamental design for a hard disk drive adapter, as shown and described.

DESCRIPTION

FIG. 1 is a first perspective view of a hard disk drive adapter showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the hard disk drive adapter that form no part of the claimed design.

1 Claim, 8 Drawing Sheets
